BOOT RACK

George K. Desmond, 619 N. River,
Independence, Mo. 64050

Filed Mar. 23, 1967, Ser. No. 6,346

Term of patent 7 years

(Cl. D33—3)

Fig.1.

Fig.2.

Fig.3.

Fig.4.

FIGURE 1 is a perspective view of a boot rack showing my design wherein the article is provided with threaded rod extensions for through-the-wall installation;

FIG. 2 is a front elevational view thereof;

FIG. 3 is a side elevational view thereof; and

FIG. 4 is a perspective view of the boot rack of FIGURE 1 wherein the terminal rod extensions are omitted and the circular plates have screw receiving openings.

I claim:

The ornamental design for a boot rack, as shown and described.
